SHIELDED CATHODE

Beatrice Pearson De Lany, 36 La Gorce Circle, Miami Beach, Fla., and Paul L. Copeland, 17 W. 80 Oak Lane, Bensenville, Ill.

Filed Oct. 14, 1963, Ser. No. 315,861
11 Claims. (Cl. 313—199)

This invention relates to a cold cathode glow discharge gas tube and in particular to a tube of the type described having a compound cathode which substantially reduces sputter and evaporation of the cathode material.

A primary purpose of the invention is to provide a glow discharge tube in which the electrodes, which may be similar, are formed with a hole, and there are means within the hole providing a region of low electric field adjacent the electron emitting surface of the electrode.

Another purpose is a compound cathode for use in a tube of the type described in which there are means within the hole of the cathode for slowing the positive ions prior to impingement or bombardment on the electron emitting surface of the cathode.

Another purpose is a tube of the type described including a generally cylindrical or tubular cathode and a screen placed within the hole of the cathode and maintained at a potential slightly more positive than that of the cathode to slow down the positive ions prior to impingement on the electron emitting surface of the cathode.

Another purpose is a compound cathode of the type described in which the plasma within the cathode hole is positioned within the screen.

Another purpose is an improved tube construction of the type described suitable for providing illumination and for other purposes, such as rectifiers, relays, oscillators and regulators.

Other purposes will appear in the ensuing specification, drawings and claims.

The invention is illustrated diagrammatically in the following drawings wherein:

FIGURE 1 is a side elevation of a tube of the type described,

FIGURE 2 is an enlarged section along the axis of one of the electrodes illustrated in FIGURE 1,

FIGURE 3 is an end view of the electrode illustrated in FIGURE 2,

FIGURE 4 is a diagram on which are plotted the curves illustrating the effect of the presence or absence of the shield,

FIGURE 5 is a section illustrating a modified form of the invention in which only a single cathode of the type disclosed in FIGURE 2 is used,

FIGURE 6 illustrates a further modification of the electrode arrangement in which a plurality of metal sheets is used, and

FIGURE 7 illustrates diagrammatically the zigzag path of a neutral molecule in migrating between a grid plate and an emitter plate.

The efficiency of ionization of a hollow cathode makes it attractive for use in applications of glow discharge tubes, for example in lighting tubes. The current density of such cathodes is substantially higher than for a simple flat cathode. Heretofore, pronounced sputtering has made the use of such a hollow cathode undesirable for lighting. Sputtering reduces the life of the cathode as it destroys any layer placed on the surface of the

2

cathode to reduce the work function. Furthermore, the material removed from the cathode is deposited close to the cathode orifice where the discharge concentrates. Since the material of the cathode is of necessity an electrical conductor, and is ordinarily a metal or a semi-conductor or an alloy of a metal, this reduces the insulation of parts close to the cathode which may seriously limit the effective life of any control device using the hollow cathode. Also, since the deposit is opaque, the walls of the tube tend to become black and there is a substantial reduction in illumination. The present invention is concerned with reducing sputtering so as to make a hollow cathode-type electrode usable in illumination tubes.

Sputtering depends upon the energy of the ions striking the cathode surface. It has been known that sputtering is negligible for ion energies of less than about 20 electron volts, although the exact critical energy for sputtering depends on the kind of ion and the nature of the cathode surface. This invention is directed to providing positive ion impingement of the cathode surface of a sufficient low energy to prevent or substantially reduce sputtering.

Successful maintenance of a satisfactory glow discharge depends on positive ions producing secondary electron emission. It has been determined that at low energies there is little dependence of secondary electron emission on the kinetic energy of the positive ions. Low speed ions are effective in liberating secondary electrons, but they do not cause sputtering of the cathode. By reducing the speed or energy of the positive ions that are to impinge the electron-emitting surface of the cathode, it is possible to prevent sputtering. This reduction in the kinetic energy of the positive ions can be accomplished by providing a low electric field in the space through which the positive ions move. There is low gain in energy which passes through such an electric field.

The ions are interacting by various mechanisms with the molecules of the gas through which they are moving, and, if the electric field is low, they lose more energy in these interactions than they gain from their acceleration in the electric field and in consequence of this, they slow down. Thus the energy of the positive ions impinging on the cathode can be reduced to values so low that the sputtering from the cathode surface is negligible.

The kinetic theory of gases provides the means for checking the feasibility of accomplishing these objectives. A gas filling the tube consists of a very large number of extremely small molecules in very rapid motion. For hydrogen gas at room temperature, the effective speed of the molecules is about a mile per second. For larger molecular weights, the molecules have less average speed. For example, the molecules of argon travel less than a quarter as fast as those of hydrogen. Pressure on the walls of the containing vessel is caused by the momentum transfer when these molecules strike and are reflected from the walls.

A molecule under laboratory conditions is unlikely to travel with constant velocity from one wall of the container to the opposite wall. Ordinarily it collides repeatedly with other molecules and has its momentum changed many times. The changes in velocity may be large and a molecule follows a zigzag path. The average distance between collisions is called the mean free path. Even in gases at a relatively low pressure for the glow discharge, namely 1.0 Torr (1.0 mm. Hg) these

mean free paths for momentum transfer are quite small. For hydrogen gas (H_2) at $25^\circ C$, the mean free path is 0.0093 cm. while other gases have mean free paths which are comparable. A gas of perfect spheres, to have the same mean free path as hydrogen, would require that the spheres be only 2.75×10^{-8} cm. in diameter. While to have the same mean free path as argon would require ideal spheres 3.67×10^{-8} cm. in diameter. The area of a circle having a radius equal to the diameter of the ideal sphere is called the kinetic theory cross section of the molecule.

Individual molecules change their position by zigzag paths, and for the individual straight line segments each direction in space is equally likely. The distance which a molecule will travel in migrating between two parallel planes is very much greater than the separation between these planes. If, for example, the planes are separated by " n " mean free paths, on the average the number of mean free paths which a molecule travels in migrating from one plane to the other is " n^2 ".

These considerations apply in a general way also to the ions passing through the shield on their way to the cathode. If there is no electric field in this region, they are simply slowed down in their collisions with the molecules of the gas. After losing their forward momentum, they follow zigzag paths similar to the molecules in the preceding discussion. If there is a low electric field in the region, the general considerations are much the same except that the positive ions between the collisions have a small acceleration in the direction of the field. On the average, in consequence of this acceleration, there is a relatively slow drift of the ions in the direction of the field.

One means of providing such a low electric field adjacent the electron-emitting surface of the cathode is to provide a shield or screen which is at the same or a slightly different potential than that of the cathode. Such a screen or shield establishes a potential difference between itself and the anode such that the plasma of the discharge is set up within it. The field in the neighborhood of the cathode surface is reduced and there is a space through which the ions drift with small acceleration before they impinge on the cathode surface. Such a shield does not substantially reduce the number of electrons liberated from the surface by the positive ions, but does reduce sputtering and prolongs effective cathode and tube life.

As illustrated in FIGURE 1, a tube 10 may include an air impervious envelope 12, for example glass or the like, within which is a suitable gas under a sufficient pressure. The noble or other inert gases, mercury vapor, or mixtures of them are satisfactory gases. At each end of the tube 10 there is an electrode 14 and when the tube, either clear or coated with phosphors, is used for lighting the electrodes will be substantially identical. This is conventional when tubes of this type operate on alternating current, and each of the electrodes are alternately functioning as an anode and cathode.

FIGURE 2 illustrates the details of the electrodes 14. Each of the electrodes may include a generally cylindrical or tubular mass 16 which may be formed of any material which suffices to provide strong electron emission when positive ions impinge upon it. Tungsten, tantalum, molybdenum, nickel and stainless steel may all be satisfactory. Any one of these materials may have a coating of a substance which lowers the work function. There is a hole 18 positioned within the mass 16 and preferably the hole is along the axis of the electrode. A practical size, although the invention should not be so limited, is to have the mass 16 with a diameter of about one-half inch with the hole 18 having a diameter of about $1/16$ inch.

Positioned within the hole 18 and spaced therefrom is a fine screen or the like 20 which may be formed of aluminium, magnesium, tantalum or some other satisfac-

tory metal or semi-conductor or alloy. These materials may have oxide coatings when this reduces the sputtering of material. The screen 20 may extend the length of the hole, although this is not necessary. A lead-in 22 for the screen passes through an insulating bushing 24 at the end of the hollow cathode. A lead-in 26 provides the potential for the cathode and preferably the potential difference between the screen and the cathode is very slight with the screen being a small amount more positive than the cathode. A suitable biasing resistor, not shown, may be placed between leads 22 and 26 so that the leads may then be connected to a common source of alternating current.

When the tube is operating the plasma with its column of positive ions will be formed within the screen 20. The positive ions thus formed in the plasma are then moved by the potential of the cathode and the screen to impinge on the interior surface 28 of the hole 18 to produce the secondary emission for forming the glow discharge in the tube. The screen is to be located in the cathode dark space of the glow. The screen is used to reduce the electric field in the portion of the cathode dark space near the cathode surface. In this region of low potential gradient, there is little acceleration of the positive ions as they travel to the cathode. Preferably the spacing between the screen and the surface 28 or the width of the sheath is such that the mean free path of the positive ions moving across this sheath is small relative to its thickness. Most of the ions lose their kinetic energy near the cathode and the low speed ions formed cannot gain much energy before coming in contact with the principal electron emitting surface and there is therefore little sputtering.

The screen or shield should not be limited to any particular size or thickness as what is important is to provide a particular potential at this point. The screen should be sufficiently small however to keep its sputter at a negligible level. Any one of the materials listed may be satisfactory for forming the screen. In like manner the size and configurations of the cathode mass may vary widely. A cylindrical shape is not necessary. The gas pressures and the type of gas will vary and particular combinations of gas pressure, cathode material, and screen material may be used in different applications of lighting.

The effectiveness of a shield in improving the electrical characteristics of a hollow cathode is an important advantage. For example, we have used a pair of plates, each 6 inches square, separated from one another by 3 inches and operated with such gas pressures that the interior surfaces of the arrangement serve as sources of electron emission. For purposes of comparison, one such cathode was made without a shield. The second parallel plate cathode was identical to the first except that each plate of the pair had a shield of fine wires near the surface facing the opposite plate. Each wire of the shield was separated by 3 mm. from the interior surface of the nearer parallel plate and the spacing between adjacent wires was 2 mm. The entire surface of each plate was shielded by such a wire screen. Both plates of each cathode were connected directly to a source of negative potential, an easy comparison between the operation of the shielded and the unshielded parallel plate was obtained by electrically connecting each shield to the cathode plate near it. A conventional anode was made positive with respect to the cathode by a measured amount, and the total current passing from each cathode pair to the anode was measured. At gas pressures of 0.1 Torr (100μ) or greater the plasma of the discharge was established between the parallel plates. For equal potential differences, the current in the shielded cathode was substantially larger than the current in the unshielded cathode. Representative data is plotted in FIGURE 4, and it is seen that including shields in a cathode cavity results in about twice and often considerably more than

twice the current at a given potential difference between anode and cathode.

When milliammeters are connected to measure the currents in the shields and parallel plates separately and the potentials are made substantially the same by connecting the milliammeters to the negative terminal of the power source, the current supplied by the shields is only slightly less than that supplied by the two plates. As the potential of the shields is raised, the shield current decreases gradually until it reaches zero when the potential of the shields is about 200 volts positive with respect to the parallel plates. This represents the "floating potential" of the shields. Any desired potential between zero and the floating potential for the operation of the shields may be established simply by varying a resistor placed in series with the electrical connection to the shields.

When the word "sputtering" is used in the specification and claims, it is to be understood as meaning the loss of cathode material resulting from positive ion bombardment. It is to be understood that the shield in whatever form it is present does not discriminate against secondary emission of electrons but does reduce sputtering.

As used herein, the expression "a material of low work function" is to be understood as meaning a material for which the increase in potential energy of an electron, as it passes from the interior of the material to a matter-free space, is relatively small.

In particular, the electrode may take the form illustrated in FIGURE 5, in which, although there are two electrodes, only one is of the type shown generally in FIGURE 1 and in detail in FIGURES 2 and 3. There is thus in the form of FIGURE 5 an envelope 30 which is of insulating material and except for its shape it is the same as the envelope 12 within which is a suitable gas under sufficient pressure, generally as described in detail in connection with the description of FIGURE 1. Because it is identical with the electrode 14 shown in the earlier figures, the electrode which is in the smaller end of the envelope 30 carries the same reference numerals as those shown in FIGURES 1, 2 and 3 and it need not be described here. The electrical connections are also the same and preferably will include a resistance 26' as shown in FIGURE 2. In FIGURE 5, instead of two electrodes 14 as shown in FIGURE 1, a simple plate anode 31 is provided. It is connected to a lead in wire 32 which passes through the envelope 30. The structure of FIGURE 5 comprises a half wave rectifier.

FIGURE 6 illustrates a further modified form of cathode. There is shown in this figure a hollow cathode which instead of being of rounded or circular cross section as shown in FIGURE 3 comprises a plurality of parallel metal sheets 33, 33. Adjacent each is a shield 34. The shields 34 act as does the shield or screen 20 of FIGURES 2 and 3 and will normally be made of the same material as the shield 20 which has been described in detail above. In the form of FIGURE 6, the metal sheets are connected electrically or at the same potential and the electrode formed of the two plates 33 shown particularly in the form of FIGURE 6 is positioned within an envelope of suitable size and shape and is provided with a conductor the same as or equivalent to the conductor 26. Electrodes according to the form of FIGURE 6 may be used in the same manner as the electrode 14 is used, in pairs as shown in FIGURE 1, or singly with a conventional anode as shown in FIGURE 5.

The diagram of FIGURE 7 illustrates in detail a zig-zag path of a neutral molecule in migrating between the plane of the shield 34 and the plane of the emitter plate 33. A positive ion in the field free space would have a path very similar in appearance to that shown in FIGURE 7. The molecule path shown in FIGURE 7 is typical of the migration of a neutral molecule under the conditions prevailing in the tube. It is not necessarily how-

ever a precise showing of the movements of any particular molecule.

Whereas the preferred form of the invention has been shown and described herein, it should be realized that there are many modifications, substitutions and alterations thereto within the scope of the following claims.

We claim:

1. In a glow discharge gas tube, an air impervious envelope, a first electrode in said envelope effective to operate as an anode, a second electrode spaced from said first electrode and effective to operate as a cathode, said second electrode being generally cylindrical in form and having a generally cylindrical hole along its axis, a generally cylindrical screen positioned within said hole and uniformly spaced from the interior surface of said second electrode, said generally cylindrical screen being operated at a potential slightly different than that of said second electrode and being effective to produce a region of low electric field adjacent the interior surface of said second electrode from which electrons are extracted by positive ion impingement.
2. In a glow discharge gas tube, an air impervious envelope, a first electrode in said envelope effective to operate as an anode, a second electrode spaced from said first electrode and effective to operate as a cathode, said second electrode being generally cylindrical in form and having a generally cylindrical hole along its axis, a generally cylindrical screen positioned within said hole and uniformly spaced from the interior surface of said second electrode, said generally cylindrical screen being operated at a potential approximately the same as that of said second electrode and being effective to produce a region of low electric field adjacent the interior surface of said second electrode from which electrons are extracted by positive ion impingement.
3. In a glow discharge tube, an air impervious envelope, a first electrode in said envelope effective to operate as an anode, a second electrode spaced from said first electrode and effective to operate as a cathode, said second electrode including a principal electron emitting surface and an open electrically conducting structure spaced from said emitting surface a distance equal to several times the mean free path of positive ions moving thereby, said open structure being supported by the part containing said principal electron emitting surface and maintained at an electrical potential with respect to said emitting surface which is effective to reduce the electric field between said electrically conducting structure and said emitting surface.
4. The structure of claim 3 further characterized in that said second electrode is formed of a material of high electrical conductivity and includes a cavity, said electrically conducting structure being positioned within said cavity.
5. The structure of claim 4 further characterized in that said electrically conducting structure includes a conducting sheet with perforations.
6. The structure of claim 5 further characterized in that said conducting sheet with perforations is formed of a screen.
7. The structure of claim 3 further characterized in that said second electrode is formed of a material of high electrical conductivity and has an electron emitting surface coated with a film of material selected for its high secondary emission under impingement of positive ions.
8. In a glow discharge tube, an air impervious envelope, a first electrode in said envelope effective to operate as an anode, a second electrode spaced from said first electrode and effective to operate as a cathode, said second electrode having a hole, and means within said hole for producing a region of low electric field adjacent the interior surface of said electrode from which electrons are extracted by impingement of positive ions, said means being effective to reduce the electric field over

a distance, from any point on the interior electron producing surface, larger than the average mean free path of the positive ions.

9. The structure of claim 8 further characterized in that the means for producing a region of low electric field provides a shield of low electric field adjacent the electron emitting surface and of a thickness several times the average mean free path of the positive ions.

10. The structure of claim 8 further characterized in that the plasma of the discharge is positioned within said means.

11. The structure of claim 8 further characterized in

that the means producing a region of low electric field includes an open electrically conducting shield, the material of which is selected for its low rate of sputter under bombardment by positive ions.
